UNITED STATES PATENT OFFICE.

CHARLES E. THOMAS, OF LOS ANGELES, CALIFORNIA.

ROTATING ROTARY JAR.

Application filed October 29, 1924. Serial No. 746,534.

To all whom it may concern:

Be it known that I, CHARLES E. THOMAS, a citizen of the United States, residing at Los Angeles, in the county of Los Angeles and State of California, have invented new and useful Improvements in Rotating Rotary Jars, of which the following is a specification.

This invention relates to improvements in rotary jars adapted to be used in drilling deep wells, such as oil wells.

It is an object of this invention to provide a rotary jar, which is adapted to be mounted on the lower end of a drill tube and to which the drill or tooth is adapted to be connected and which is of such construction that the jar will normally cause the tool to rotate with the drill tube.

A further object of this invention is to provide means in the rotary jar for disengaging the connection between the tool and the drill tube so that one member of the jar may be lifted so as to impart an upward jar or impact upon the other member to which the tool is attached.

With the foregoing and other object in view which will be made manifest in the following detailed description and pointed out in the appended claims, reference is had to the accompanying drawings for an illustrative embodiment of the invention, wherein:

Figure 1 is a vertical section taken through the improved rotary jar substantially upon the line A—A of Fig. 5, showing the rotary jar in normal position whereby the tool is caused to rotate with the drill tube;

Fig. 2 is a section similar to Fig. 1, the rotary jar being shown in position preparatory to imparting an upward impact or jar to the tool;

Fig. 3 is also a section similar to Fig. 1, the jar being shown in position after having imparted an upward impact or jar to the tool;

Fig. 4 is a horizontal section taken substantially on the line 4—4 of Fig. 2;

Fig. 5 is a horizontal section taken substantially on the line 5—5 of Fig. 1;

Fig. 6 is an enlarged vertical section taken on the line 6—6 of Fig. 1;

Fig. 7 is a side elevation of means which may be employed for releasably holding the rotary jar in the position shown in Fig. 1; and

Fig. 8 is a top plan view of Fig. 7.

Referring to the accompanying drawings wherein similar reference characters designate similar parts throughout, it is to be understood that the improved rotary jars employs the elasticity of the drill tube for producing the upward impact or jar upon the tool, which may have become stuck in the bottom of the well. The jar consists of a sleeve 10 which has its upward end threaded, as at 11, so that the sleeve may be secured to the lower end of the drill tube 12. Upon opposite sides of the interior of the sleeve 10 there are formed projections 13.

Within the sleeve 10 there is disposed a mandrel 14 capable of sliding movement relatively to the sleeve 10. The mandrel 14 is provided with a longitudinal bore 15 extending therethrough which permits circulation fluid to pass from the drill tube 12 to the tool T, which may be secured upon the lower end of the mandrel 14. Upon the opposite sides of the mandrel 14 there are formed a pair of projections 16 which, as clearly shown in Fig. 5, are adapted to fit between the projections 13 upon the sleeve 10. In the position shown in Fig. 1, the projections 13 fit between the projections 16 formed upon the mandrel 14 and cause the mandrel 14 and the tool T to rotate with the sleeve 10 and the drill tube 12. The upper end of the mandrel 14 is provided with an enlarged head 17, and bosses 18 are formed upon the mandrel 14, which extend downwardly from the head 17. The width of the bosses 18 is equal to the width of the projections 16 formed upon the mandrel 14, so that the projections 13 formed upon the sleeve 10 may slide between the bosses 18.

As clearly shown in Fig. 2, the top of the head 17 is recessed, as at 19, to receive packing 20, which is held in place by means of a circular plate 21 secured as by screws 22. The packing 20 bears against the interior surface of the sleeve 10 and prevents the escape of the circulation fluid between the head 17 and the sleeve 10. As indicated in Fig. 1, one upper corner of each of the projections 16 formed upon the mandrel 14 is beveled off, as at 23, and in a corresponding manner, one lower corner of each of the projections 13 upon the sleeve 10 is beveled off, as at 24. As clearly shown in Fig. 6, the lower edges of the projections 13 formed upon the sleeve 10 are recessed as at 25, and the interior diameter of the

sleeve 10 adjacent the bottom of the sleeve is enlarged, as indicated at 26. A ring 27 is positioned adjacent the bottom edges of the projections 13 upon the sleeve 10 and this ring carries a pair of spring fingers 28 upon which are mounted dogs 29. A coil spring 30 is positioned beneath the ring 27, and below the coil spring 30 there is positioned a second ring 31 carrying upstanding arms 31^a.

Below the ring 31 there is placed a sleeve 32 which is of a reduced upper diameter, as indicated at 32^a, which is threaded so that the sleeve 32 may be secured to the lower end of the sleeve 10. The portion 32^a provides an annular shoulder which holds the ring 31 in proper position. The lower end of the sleeve 32 is internally threaded to receive a nut 32^b, against which is positioned a channel-shaped member 33 which holds packing 34 adapted to bear against the mandrel 14 and prevent the upward flow of circulation fluid thereabout. A nut 35 holds the channel-shaped member 33 in position against the nut 32^b. The ring 31 is provided with one or more vertical grooves which receive pins 36 formed upon the interior of the sleeve 10. The pins 36 prevent rotation of the ring 31 within the sleeve 10.

The ring 27 is provided with upwardly tapering lugs 37 which are receivable in corresponding recesses formed upon the projections 13. The lugs 37 are intended to maintain the ring 27 in its correct position within the sleeve 10, it being understood that the dogs 29 and the spring fingers 28 within the recesses 25 keep the ring 27 in approximately its proper position. Small notches or recesses 40 are formed upon the opposite sides of the mandrel 14 and are adapted to receive the dogs 29 carried by the spring members 28, it being understood that the spring fingers 28 serve to urge the dogs 29 toward the center of the mandrel 14.

The operation of the rotary jar is as follows: The dogs 29 engage the recesses 40 formed in the mandrel 14 when the sleeve 10 is in its lowermost position, as in the position shown in Fig. 1. The projections 13 and 16 are then in engagement with each other and the tool T is caused to rotate with the sleeve 10 and the drill tube 12. If for any reason, the tool T should become stuck, so that it cannot be rotated, it is then desirable to impart an upward jar upon the tool T so as to loosen it. The drill tube 12 is then raised, which causes an upward movement of the sleeve 10. The dogs 29 being within the recesses 40 prevent the upward movement of the ring 27, and the spring 30 is therefore compressed. The upward movement of the sleeve 10 causes the upward movement of the ring 31 and the upstanding arms 31^a, and as the arms 31^a move upwardly about the mandrel 14 they engage the spring fingers 28 and the dogs 29 and cause the removal of the dogs 29 from within the recesses 40. After the dogs 29 have been removed from the recesses 40, the ring 27 assumes its original position, as shown in Fig. 7, and the dogs 29 are disposed completely within the recesses 25 formed in the projections 13. As shown in Fig. 1, the bosses 18 formed upon the mandrel 14 have an angular relation to the projections 16. As the sleeve 10 is lifted, the projections 13 formed upon the sleeve slide upwardly from between the projections 16 so as to occupy the position shown in Fig. 2. Because of the angular relation between the bosses 18 and the projections 16, the projections 13 engage the lower surfaces of the bosses 18.

When the rotary jar is in the position shown in Fig. 2, an upward strain is placed upon the drill tube 12. Because of the length of the drill tube, a comparatively small upward strain, for instance 60,000 lbs., will cause a considerable stretching of the drill tube, the amount of stretching being determined by the length of the drill tube and by the cross sectional area of the drill tube. In the preferred embodiment of the invention, the vertical length of the bosses 18 is about six inches and therefore a sufficient strain is placed upon the drill tube 12 to stretch the tube at least six inches and preferably more. After the drill tube 12 has been stretched, the drill tube together with the sleeve are slightly rotated toward the right. This causes the projections 13 which are in engagement with the bosses 18 as shown in Fig. 2, to slide over the ends of the bosses 18 and upon becoming disengaged from the bosses 18, to be pulled upwardly against the head 17 because of the elasticity of the drill tube 12. The projections 13 upon slipping off the ends of the bosses 18 and striking the head 17 impart a sudden upward blow to the head 17 and consequently to the mandrel 14 and the tool T. After a blow has been imparted to the head 17 by the projections 13, the drill tube 12 is then lowered. Because of the fact that the sleeve 10 has been slightly rotated so as to disengage the projections 13 from the bosses 18, the projections 13 are then partially in alignment with the projections 16. However, upon lowering the drill tube 12 and the sleeve 10, the inclined or beveled corners 24 of the projections 13 engage the inclined or beveled corners of the projections 16 and tends to swing the sleeve 10 and the drill tube 12 back to their original position, permitting the projections 13 to slide downwardly between the projections 16 and permitting the dogs 29 to re-enter the recesses 40, thereby resiliently holding the mandrel 14 in its original or normal position, as shown in Fig. 1. As will readily

- be understood, the tool is designed to employ the elasticity of the drill tube 12 to cause the upward blow to be given to the mandrel 14. This blow given in the above 5 described manner is much sharper and of much greater magnitude than will be produced by attempting to lift the drill tube 12 so as to cause the projections 13 to strike the bosses 18 or the head 17 for the reason that 10 the inertia of the long string of drill tube 12 prevents the drill tube and the sleeve 10 together with the projection 13 from attaining a high upward velocity. It will be readily understood that if a single blow 15 produced by the improved rotary jar in the above described manner is insufficient to loosen the tool T, the operation may be repeated as often as necessary until the tool T has been completely loosened.
- 20 The rings 31 and 27 together with the spring 30 and the arms 31^a together with the dogs 29 are not absolutely essential to the operation of the jar as above described. However, these elements are preferably employed so that the tool T and the mandrel 14 may be releasably retained in their normal positions as shown in Fig. 1, even though the tool T is not actually bearing upon the bottom of the well.
- 25 It will be understood that various changes in the detail of construction may be made without departing from the spirit or scope of this invention as defined by the appended 30 claims.
- 35 I claim:
1. A rotary jar comprising a sleeve attachable to a drill tube, a mandrel slidable within said sleeve, projections formed upon the interior surface of said sleeve and upon the exterior surface of said mandrel adapted to interfit to cause said mandrel to rotate with said sleeve, and a head formed upon said mandrel adapted to be engaged by the projections upon said sleeve, whereby upward movement of said sleeve will impart an upward jar to said mandrel.
  2. A rotary jar comprising a sleeve attachable to a drill tube, a mandrel slidable in said sleeve to which a tool is adapted to be secured, projections formed upon the interior surface of said sleeve and upon the exterior surface of said mandrel adapted to engage and cause said mandrel to rotate with said sleeve, a head formed upon said mandrel, and bosses formed upon said mandrel adjacent said head adapted to be engaged by the projections upon said sleeve upon upward movement thereof, whereby by applying an upward pull to said sleeve and rotating said sleeve, the projections formed upon said sleeve may be disengaged from said bosses and strike said head, thereby imparting an upward jar to said mandrel, said bosses being so arranged with respect to the projections upon said mandrel as to be engaged by the projections upon said sleeve upon vertical movement of said sleeve with respect to said mandrel.
  3. A rotary jar comprising a sleeve attachable to a drill tube, a mandrel slidable in said sleeve to which a tool is adapted to be secured, projections formed upon the interior surface of said sleeve and upon the exterior surface of said mandrel adapted to engage and cause said mandrel to rotate with said sleeve, a head formed upon said mandrel, and bosses formed upon said man-
- within said sleeve, projections formed upon the interior surface of said sleeve and upon the exterior surface of said mandrel adapted to interfit to cause said mandrel to rotate with said sleeve, a head formed upon said mandrel adapted to be engaged by the projections upon said sleeve, whereby upward movement of said sleeve will impart an upward jar to said mandrel, and spring means for releasably holding said mandrel and sleeve in position whereby said projections upon said sleeve and mandrel are disposed in interfitting relation.
4. A rotary jar comprising a sleeve attachable to a drill tube, a mandrel slidable in said sleeve to which a tool is adapted to be secured, projections formed upon the interior surface of said sleeve and upon the exterior surface of said mandrel adapted to engage and cause said mandrel to rotate with said sleeve, a head formed upon said mandrel, bosses formed upon said mandrel adjacent said head adapted to be engaged by the projections upon said sleeve upon upward movement thereof, whereby by applying an upward pull to said sleeve and rotating said sleeve, the projections formed upon said sleeve may be disengaged from said bosses and strike said head, thereby imparting an upward jar to said mandrel, and spring means for releasably holding said sleeve and mandrel in such position that the projections upon said sleeve and mandrel are engaged.
5. A rotary jar comprising a sleeve attachable to a drill tube, a mandrel slidable in said sleeve to which a tool is adapted to be secured, projections formed upon the interior surface of said sleeve and upon the exterior surface of said mandrel adapted to engage and cause said mandrel to rotate with said sleeve, a head formed upon said mandrel, and bosses formed upon said mandrel adjacent said head adapted to be engaged by the projections upon said sleeve upon upward movement thereof, whereby by applying an upward pull to said sleeve and rotating said sleeve, the projections formed upon said sleeve may be disengaged from said bosses and strike said head, thereby imparting an upward jar to said mandrel, said bosses being so arranged with respect to the projections upon said mandrel as to be engaged by the projections upon said sleeve upon vertical movement of said sleeve with respect to said mandrel.
6. A rotary jar comprising a sleeve attachable to a drill tube, a mandrel slidable in said sleeve to which a tool is adapted to be secured, projections formed upon the interior surface of said sleeve and upon the exterior surface of said mandrel adapted to engage and cause said mandrel to rotate with said sleeve, a head formed upon said mandrel, and bosses formed upon said man-

drel adjacent said head adapted to be engaged by the projections upon said sleeve upon upward movement thereof, whereby by applying an upward pull to said sleeve 5 and rotating said sleeve, the projections formed upon said sleeve may be disengaged from said bosses and strike said head, thereby imparting an upward jar to said mandrel, the engaging surfaces between said 10 bosses and the projections upon said sleeve being substantially flat, horizontal surfaces.

7. A rotary jar comprising a sleeve attachable to a drill tube, a mandrel to which a tool is adapted to be connected slidable 15 within said sleeve, projections formed upon said sleeve and mandrel adapted to engage to prevent relative rotation between said sleeve and mandrel, a head formed upon said mandrel, bosses formed upon said mandrel, 20 drel extending downwardly from said head, recesses formed upon said mandrel, a ring disposed within said sleeve, spring actuated dogs carried by said ring and receivable in said recesses, and means for withdrawing 25 said dogs from said recesses upon upward movement of said sleeve relatively to said mandrel.

8. A rotary jar comprising a sleeve attachable to a drill tube, a mandrel to which a tool is adapted to be connected slidable 30 within said sleeve, projections formed upon said sleeve and mandrel adapted to engage to prevent relative rotation between said sleeve and mandrel, a head formed upon said mandrel, bosses formed upon said mandrel 35 extending downwardly from said head, recesses formed upon said mandrel, a ring disposed within said sleeve, spring actuated

dogs carried by said ring and receivable in said recesses, means for withdrawing said 40 dogs from said recesses upon upward movement of said sleeve relatively to said mandrel, and packing disposed between said mandrel and said sleeve adjacent the top and bottom thereof. 45

9. A rotary jar comprising a sleeve, a mandrel slidable within said sleeve, projections formed upon the interior surface of said sleeve and the exterior surface of said mandrel adapted to interfit causing the 50 mandrel to rotate with the sleeve, a head formed upon the mandrel, and bosses extending downwardly from the head and engageable by the projections upon said sleeve, said bosses being so arranged as to have portions directly above the projections upon said sleeve when the projections upon the sleeve are interfitting with the projections upon said mandrel, whereby upon a straight upward sliding of the sleeve with respect to 55 the mandrel, the projections upon the sleeve will engage the bosses, and upon rotation of the sleeve the projections will disengage the bosses and strike the head. 60

10. In a rotary jar having a mandrel and 65 a sleeve slidable thereon, means for causing the mandrel and the sleeve to be locked against relative rotation, means for causing the sleeve upon upward movement to impart a jar to the mandrel, and means for releasably retaining the mandrel and sleeve in 70 such position as to be locked against relative rotation.

In testimony whereof I have signed my name to this specification.

CHAS. E. THOMAS.
